US00D638977S

(12) **United States Design Patent**
Heyrman

(10) **Patent No.:** **US D638,977 S**
(45) **Date of Patent:** **** May 31, 2011**

(54) **LUMINAIRE**

(75) Inventor: **Koen Heyrman**, Melsele (BE)

(73) Assignee: **Koninklijke Philips Electronics N.V.**,
Eindhoven (NL)

(**) Term: **14 Years**

(21) Appl. No.: **29/369,313**

(22) Filed: **Sep. 7, 2010**

(30) **Foreign Application Priority Data**

Mar. 18, 2010 (EM) 001683061-0003

(51) **LOC (9) Cl.** **26-03**

(52) **U.S. Cl.** **D26/85**

(58) **Field of Classification Search** D26/85,
D26/87, 88, 90, 91, 118, 128-130, 137, 144;
362/147, 404-408, 431, 432

See application file for complete search history.
